UNITED STATES PATENT OFFICE.

LOUIS E. SADLER, OF ATTLEBORO, MASSACHUSETTS, ASSIGNOR TO THE F. H. SADLER COMPANY, OF ATTLEBORO, MASSACHUSETTS, A CORPORATION OF RHODE ISLAND.

ORNAMENTAL FINGER-RING.

SPECIFICATION forming part of Letters Patent No. 776,804, dated December 6, 1904.

Application filed June 28, 1904. Serial No. 214,513. (No model.)

To all whom it may concern:

Be it known that I, LOUIS E. SADLER, a citizen of the United States, residing at Attleboro, in the county of Bristol and State of Massachusetts, have invented a new and useful Improvement in Ornamental Finger-Rings, of which the following is a specification.

This invention has reference to an improvement in the construction of ornamental finger-rings, and more particularly to an improvement in the means for securing an ornamental head to the ring.

The object of my invention is to secure the ends or joint of the ring and ornamental head permanently together without the use of solder.

A further object of my invention is to construct a plated finger-ring having an ornamental head so that the entire exterior surface of the ring is covered by the plate, which may be of gold or other precious metals.

My invention consists in the peculiar and novel construction of an ornamental finger-ring having a joint in which is a circular aperture formed by semicircular abutting ends, a tubular rivet extending upward through the aperture, a cap adapted to secure the semicircular abutting ends together, a plate secured on the cap by the tubular rivet, and an ornamental head secured to the plate by rolling lips on the head under the plate, as will be more fully set forth hereinafter.

Figure 1 is a side view of my improved ornamental finger-ring. Fig. 2 is a face view of the ring, showing the ornamental head. Fig. 3 is a face view showing the semicircular abutting ends forming the aperture in the joint of the ring. Fig. 4 is a face view showing the tubular rivet in the aperture and the abutting ends secured together by the cap. Fig. 5 is a face view showing the plate secured on the cap by the tubular rivet. Fig. 6 is an enlarged detail sectional view of the head of the ring, taken on line X X of Fig. 2; and Fig. 7 is an enlarged detail sectional view of the head, taken on line Y Y of Fig. 2.

In the drawings, *a* indicates the hoop of

the ring, *b* the tubular rivet, *c* the cap, *d* the plate, and *e* the ornamental head, of my improved ornamental finger-ring. The hoop *a* has the abutting semicircular ends *a'* *a'*, forming the circular aperture *a*², as shown in Fig. 3. The tubular rivet *b* extends upward through the aperture *a*², with its head *b'* against the inner surface of the ring. The cap *c*, having the central hole *c'* in its top coinciding with the aperture *a'* and the downwardly-extending sides *c*² *c*² shaped to fit the semicircular ends *a'* *a'*, is placed over the ends with the tubular rivet *b* extending through the hole *c'* in the cap and secured to the ends by rolling the sides *c*² *c*² under the ends, thus securing the ends together, as shown in Figs. 4 and 7. The plate *d*, shaped to approximately fit the ornamental head *e* and having the central hole *d'*, is secured on the cap *c* by upsetting the end of the tubular rivet *b* through the hole *d'* onto the plate, as shown in Fig. 5, and the ornamental head *e*, having the downwardly-extending lips *e* *e'* stamped from sheet metal, is secured to the plate *d* by rolling the lips *e* *e'* under the plate *d*, as shown in Fig. 7.

By the use of my improved construction in ornamental finger-rings a strong rigid ring is constructed without the use of solder, and in plated or gold-filled rings, to which my invention is particularly applicable the entire exterior surface is covered with the plate of precious metal, which is uninjured by soldering.

It is evident that the head *b'* of the tubular rivet *b* could be secured under the top of the cap *c* between the cap and the outer surface of the ring and that the ornamental head *e* could be constructed to form the setting for a jewel or could be of any design or configuration desired without materially affecting the spirit of my invention.

Having thus described my invention, I claim as new and desire to secure by Letters Patent—

1. An ornamental finger-ring having a hoop with semicircular abutting ends forming a circular aperture, an ornamental head, means for securing the abutting ends of the hoop to

gether without solder, and means for securing the ornamental head to the hoop without solder, as described.

2. In an ornamental finger-ring, the combination with a hoop having abutting ends forming a joint in which is a circular aperture, of

a tubular rivet, a cap having a hole for the tubular rivet, and sides adapted to fit over and under the abutting ends of the hoop to secure the tubular rivet to the hoop, as described.

3. In an ornamental finger-ring, the combination with a hoop having abutting ends forming a joint in which is a circular aperture, of

a tubular rivet, a cap having a hole for the tubular rivet, and sides adapted to fit over and

under the abutting ends of the hoop to secure the tubular rivet to the hoop, and a plate hav-

ing a hole through which the tubular rivet ex-

tends and is upset to secure the plate to the

hoop, as described.

4. An ornamental finger-ring consisting of a hoop having semicircular abutting ends forming a joint in which is a circular aperture, a tubular rivet extending through the aperture,

a cap having a hole for the tubular rivet and sides adapted to fit over and under the semi-

circular abutting ends of the hoop, a plate hav-

ing a central hole through which the tu-

bular rivet extends secured on the cap by up-
setting the end of the rivet onto the plate, and 30
a sheet-metal ornamental head having lips se-
cured over the plate by rolling the lips under
the plate, as described.

5. An ornamental finger-ring consisting of a hoop having semicircular abutting ends, a tu-

bular rivet, a cap having a hole for the tubu-

lar rivet through which it extends and sides

adapted to fit over and under the semicircular

abutting ends of the hoop, a plate having a

central hole through which the tubular rivet 40

extends secured on the cap by upsetting the

end of the rivet onto the plate, and an orna-

mental head having lips secured over the plate

by rolling the lips under the plate, as described.

6. In an ornamental finger-ring, the combi-

nation of a hoop *a*, a tubular rivet *b*, a cap *c*,

a plate *d*, and an ornamental head *e*, as shown

and described.

In testimony whereof I have signed my name

to this specification in the presence of two sub-

scribing witnesses.

LOUIS E. SADLER.
